UNITED STATES PATENT OFFICE

2,475,638

TUNING CIRCUIT FOR HIGH-FREQUENCY RECEIVERS

Joseph A. Worcester, Jr., Fairfield, Conn., assignor to General Electric Company, a corporation of New York

Application September 28, 1946, Serial No. 700,143

5 Claims. (Cl. 250—40)

1

My invention relates to apparatus for receiving high frequency waves and, in particular, for receiving a plurality of bands of short waves, some of which are modulated in amplitude and others of which are modulated in frequency. The primary object of my invention is to provide new and improved circuits for tuning radio receivers over a plurality of bands.

It is another object of my invention to provide a new and improved tuning circuit for radio receivers in which a variable element employed for tuning over one of a pair of bands of high frequencies is utilized as a device for spread-tuning over the other band of high frequency waves.

It is still another object of my invention to provide a new and improved multi-band receiver in which a single variable tuning element is utilized for tuning the circuits of the receiver over all of the high frequency bands of the receiver.

One of the features of my invention consists in connecting a variable inductance, which is employed to tune a radio receiver over a first band of high frequencies, in series with a fixed inductance, the range of the tuning inductance being restricted by a sufficient amount to allow the circuit to be tuned over the range of another band of high frequencies.

Still another feature consists in employing similar tuning arrangements in both the oscillator and radio frequency circuits of a receiver adapted to receive both amplitude modulated high frequency waves of short wave length and frequency modulated waves, the circuits being adjusted for the reception of a particular band by merely controlling the connection of a fixed inductance in series with a variable inductance.

The novel features which I believe to be characteristic of my invention are set forth with particularity in the appended claims. My invention itself, both as to its organization and method of operation, together with further objects and advantages thereof, may best be understood by reference to the following description taken in connection with the accompanying drawing in which Fig. 1 is a circuit diagram of a portion of the high frequency circuits of a multi-band radio receiver embodying my invention, and Fig. 2 illustrates a vane tuner suitable for use in the circuit of Fig. 1.

Referring to Fig. 1, I have shown the high frequency portion of a multi-band radio receiver as comprising an antenna tuning circuit 1 which is utilized for translating signals to a radio frequency tuned circuit 2. The output of the radio

2

frequency circuit 2 is supplied to a frequency converting tube 3 where the high frequency signals are mixed with oscillations generated locally in a resonant circuit 4. The antenna tuning circuit 1 is connected through a coupling capacitor 5 to an input terminal 6 to which are supplied received high frequency signals from the usual antenna. The antenna circuit 1 comprises an inductance 7 having its lower terminal connected to ground and its upper terminal connected to a multi-position band switch 8 having a plurality of fixed contacts 9-11 and a movable contact or arm 12. The upper terminal of inductance 7 is likewise connected to the fixed contacts 10, 11 of a second multi-position band switch 13. In the switches 8, 13, as well as other switches employed in my circuit, the fixed contacts at corresponding positions are designated by like reference numerals. The inductance 7 is utilized as the variable reactance element of the tuned antenna circuit 1 and is varied in value by means of a tuning element 14 which may be, for example, a ferromagnetic core adapted to be varied in position within the turns of the inductance 7. Preferably the inductance 7 is of the type disclosed in the copending application of E. O. Peterson and E. W. Forstrom, Serial No. 698,350, filed September 20, 1946, and assigned to the assignee of the present invention.

An inductance of this type comprises a pair of juxtaposed peripherally incomplete serially connected metallic conductors. The tuning element 14 for an inductance of this type comprises a metallic vane adapted to be varied in position between the conductors to control their self and mutual inductance.

When the switch 8 is in the position shown in the drawing, the variable inductance 7 is shunted by a trimmer capacitor 15 which is connected between the contact 9 of a multi-position band switch 16 and ground. The movable contact 12 of switch 16 is directly connected to the movable contact 12 of switch 8 and through capacitor 5 to the input terminal 6. When the switches 8, 13, which are ganged together for uni-control operation, are moved to positions 10, 11, a fixed inductance 17 is connected between contacts 10, 11 of the respective switches and in series with variable inductance 7. The inductance 7 preferably is of such a value that it is resonated by the trimmer capacitor 15 over a band of frequencies employed for frequency modulated signals. This inductance is so increased by the insertion in the circuit therewith of the fixed inductance 17 that the resultant inductance

is resonated by means of a trimmer capacitor 18 which switch 16 is moved to contact 10 so that the antenna circuit is resonated over a band of short wave signals, such as signals varying from 9.4-9.8 megacycles. Similarly, when the switches 8, 13, 16 are moved to contacts 11, the inductances 7, 17 are resonated by means of trimmer capacitor 19 to receive signals in the band of short waves having a frequency from 11.6-12.0 megacycles. Tuning over each of these short wave lengths is effected by movement of the tuning element 14 relative to the winding 7, the inductance 17 being of a value that it resonates with the trimmer capacitors in the desired short wave band. The movement of the element 14 relative to the winding 7 is effective to spread the tuning of the antenna circuit 1 over these respective bands.

The antenna circuit 1 is connected to the control electrode 20 of an electron discharge device 21 having a cathode 22 connected to ground through a bias resistor 23 shunted by a capacitance 24. The anode 25 of device 21 is supplied with operating potential from any suitable source indicated by the legend B+ through a choke 26 connected to the source B+ through a multi-position switch 27. When the switch 27 is connected to contact 9 thereof, the inductance 26, which is of relatively low value, is directly connected to the source B+. However, when the switch 27 is connected to the contacts 10 and 11, inductance 26 is connected to the source through a series choke 28 having a larger value of inductance. Anode 25 is connected through a coupling capacitor 29 to the upper terminal of inductance 30 in the tuned radio frequency circuit 2. The self-inductance of the inductance 30, which is similar in construction to inductance 7, is adapted to be varied in value by means of a tuning element 31, and the lower terminal of inductance 30 is connected to ground. The tuned radio frequency circuit 2 is identical with the tuned antenna circuit 1 and includes an inductance 32 whose connections correspond to those of inductance 17 in the antenna circuit, a plurality of multi-position switches 33, 34, 35 corresponding respectively to switches 8, 13, and 16, and a plurality of trimmer capacitors 36-38 having values and functions corresponding to those of capacitors 15, 18, and 19.

The converter tube 3 is illustrated as of the pentagrid type having a control electrode 39 to which the tuned R. F. circuit 2 is directly connected. The local oscillator circuit 4 is connected between a control grid 40 and cathode 42, while anode 41 of converter 3 is connected to an output or intermediate frequency circuit 43. The screen grid 44 of converter 3 is by-passed to ground by means of a capacitor 45 and is supplied with operating potential from a suitable source of unidirectional potential indicated by the legend +.

I provide a circuit to supply locally generated oscillations for heterodyning with the amplified radio frequency waves. This local oscillator circuit 4 comprises an inductance 46 which is adapted to be varied in value by means of a movable tuning element 47. One terminal of the inductance 46 is connected to ground and the other terminal connected to contact 9 of the multi-position switch 48. The other terminal of inductance 46 is likewise connected to contacts 10 and 11 of a switch 49. The movable contact of switch 49 is connected to an intermediate tap 50 on fixed inductance 51. One terminal of inductance 51 is grounded and its other terminal is connected to the contacts 10, 11 of switch 48. By movement

of the switches 48, 49, therefore, the inductance 51 is either removed from the receiver circuit or is connected therein, with its upper portion connected in series with variable inductance 46 and its portion between tap 50 and ground connected in shunt with inductance 46. I provide a plurality of capacitances 52-54 for resonating the oscillator circuit to a desired frequency band depending upon the band of waves desired to be received by the receiving apparatus. The capacitances 52-54 are connected, respectively, to the contacts 9-11 of a three-position switch 55 in order that they may easily be shunted across the inductance selected by switches 48, 49. Capacitances 53 and 54 have their lower terminals connected to ground, while capacitance 52 is connected to ground through a choke 56 shunted by a capacitor 57. The common terminals of inductance 56 and capacitors 52, 57 are connected to the contact 9 of a multi-position switch 58. The contacts 10, 11 of switch 58 are connected to the intermediate tap 50 on inductance 51, while the movable contact of switch 58 is connected directly to the cathode 42. Cathode 42 is likewise connected to control electrode 40 through a biasing resistor 59.

In the local oscillator circuit thus described, excitation for operation during the reception of frequency modulated waves is obtained from the capacitance divider comprising the connection of the cathode 42 to the common terminals of capacitors 52, 57. Choke 56 provides a path for unidirectional currents between the cathode and ground for this connection. For reception of amplitude modulated waves in a short wave band, however, when switch 58 is connected to either contact 10 or 11, excitation to sustain oscillations of the oscillator circuit 4 is provided by the connection of the cathode to the intermediate point or tap 50 on the serially connected inductances 46, 51.

The output circuit 43 of the converter tube 3 comprises a pair of serially connected resonant circuits comprising, respectively, inductance 60, 45 capacitance 61, and inductance 62 and capacitance 63, inductances 60 and 62 being the primary windings of the usual intermediate frequency transformers. The first of these circuits is shunted by a switch 64 which, when connected to its contact 9, short-circuits the elements 60, 61 and directly connects the elements 62, 63 to ground through a by-pass capacitor 65 to a source of potential through a resistance 66. When the switch 64 is connected to its contacts 10, 11, the elements 60, 61 are connected in circuit with the source of potential and the elements 62, 63 are short-circuited. The elements 60, 61 are tuned to the intermediate frequency utilized in the reception of amplitude modulated short waves, while the elements 62, 63 are tuned to the intermediate frequency utilized in the reception of frequency modulated waves.

In my receiver circuits, the various switches are all mechanically connected for unicontrol operation so that the receiver circuits are tuned either for the reception of a frequency modulated wave or one of two bands of amplitude modulated short waves. The movable tuning elements 14, 31, 47 likewise preferably are mechanically connected for unicontrol operation so that the antenna circuit 1, the radio frequency circuit 2 and the oscillator circuit 4 are tuned simultaneously over a range of frequencies, the frequencies of the antenna circuit 1 and the radio frequency circuit 2 being identical, while the frequency of

the oscillatory circuit 4 is of a value to track with the antenna and radio frequency circuits to provide, in the anode circuit of converter 3, currents of the desired intermediate frequency. When the respective circuits have their movable contacts connected to the fixed contacts 9, the receiver is adjusted for the reception of frequency modulated waves and the antenna, radio frequency and local oscillator circuits are tuned over the band of frequency modulated signals by simultaneous movement of cores 14, 31 and 47. When it is desired, however, to receive amplitude modulated signals on either of the short wave bands, the respective switches are connected to either contacts 10 or 11 depending upon the band of frequencies desired to be received. In either of these positions, the variable inductances of the antenna and radio frequency circuits are connected in series with an inductance of a value required to resonate in the short wave bands. The values of these fixed inductances 17, 32 are such that the variable inductances 7 and 30 are sufficient to spread the tuning of the antenna and radio frequency circuits over the two bands of short waves.

In the local oscillator circuit 4, the value of inductance 46 required for the generation of oscillations of a frequency to track with the frequency modulated waves is such that, when the circuit is to be used to provide oscillations to track with waves in the short wave bands, the inductance 46 is connected in shunt with a portion of the inductance 51 and in series with the remainder thereof.

In Fig. 2 I have illustrated a variable inductance which is particularly adapted for tuning radio receiver circuits over the band of frequencies employed for frequency modulated short waves, as well as amplitude modulated short waves. The inductance illustrated in this figure comprises a pair of juxtaposed, peripherally incomplete loop-like metallic conductors 67, 68, each of which is provided with three complete legs and an incomplete inwardly extending leg 69. Preferably, the conductors are oriented by rotating one through an angle of 180° with respect to the other so that the legs 69 overlap and may be joined together by means of a rivet 70 so that the conductors are serially connected to form an inductance having a relatively low value of self-inductance. The value of both of the self and mutual inductance of the loops 67, 68 may be varied by means of a metallic vane 71 formed of any suitable material, such as copper, and which is supported to be moved linearly in a plane intermediate the planes of the conductors 67, 68. Preferably, the vane 71 is provided with a pair of longitudinal slots 72 so shaped that a desired inductance versus displacement characteristic is obtained as the vane is moved into positions interleaving the conductors 67, 68. The loops 67, 68 are provided with a plurality of outwardly extending arms 73 which are adapted to be received in suitable recesses 74 provided in a molded insulator 75, the recesses spacing the loops laterally. Insulator 75 is provided with a longitudinal slot 76 adapted to receive the outer edge of the vane 71 so that the vane moves in a predetermined manner with respect to the conductors 67, 68. I have found such an inductance to be particularly adapted for use as the inductances 7, 30, 46 in receiver circuits tuned for the reception of amplitude modulated short waves and frequency modulated waves.

An important advantage of my improved tuned circuit for multi-band radio receivers is that it utilizes the same variable inductances in the reception of both amplitude modulated short waves and frequency modulated short waves where the bands of frequency and amplitude modulated waves are widely separated in the frequency spectrum. In this way, the same variable elements are used for tuning over a plurality of bands of frequencies, reducing both the cost and the complexity of the circuits required.

While I have shown one particular embodiment of my invention, it will occur to those skilled in the art that changes and modifications may be made without departing from my invention. I therefore contemplate by the appended claims to cover all such changes and modifications as fall within the true spirit and scope of my invention.

What I claim as new and desire to secure by Letters Patent of the United States is:

1. In a radio receiver circuit for receiving both a pair of frequency modulated waves and a pair of amplitude modulated waves of short wave length, a pair of inductances of different values, one of said inductances being variable, a plurality of trimmer capacitors, and switching means for connecting a first of said capacitors in shunt with said one inductance for tuning said receiver circuit over a first band for reception of frequency modulated waves and for connecting the other of said inductances in series circuit with said one inductance and a second of said capacitors in shunt with said series circuit to tune said receiver circuit over a second band of frequencies for reception of amplitude modulated waves.

2. A multi-band radio receiver circuit comprising a pair of tunable circuits, each comprising a pair of inductances of different values, one of said inductances being variable, a plurality of capacitors, first switching means for one of said circuits for connecting a first of said capacitors in shunt with said one inductance for tuning said one circuit over a first band of frequencies with variation of said one inductance and for connecting the other of said inductances in series circuit with said one inductance and a second of said capacitors in shunt with said series circuit to tune said one circuit over a second band of frequencies, second switching means for the other of said circuits for connecting a first of the said capacitors thereof in shunt with the said one inductance thereof for tuning said other circuit over a band of frequencies displaced from said first band of frequencies and for connecting a portion of the other of said inductances thereof in series circuit with the said one inductance thereof and a second of the said capacitors thereof in shunt with said last series circuit to tune said other circuit over a band of frequencies displaced from said second band of frequencies.

3. In a multi-band radio receiver, a pair of tunable circuits each comprising a pair of inductances of different values, one of said inductances being variable, and a plurality of capacitors, switching means for a first of said circuits selectively connecting the other of said inductances in series circuit with said one inductance and different of said capacitors in shunt with said one inductance to form a circuit tunable over a given band of short wave lengths or a different high frequency band widely spaced in wave length from said given band, and switching means for the other of said pair of circuits for selectively connecting a portion of the other

of the inductances thereof in shunt with the one inductance thereof and different of said capacitors in shunt with said one inductance to form a circuit tunable over ranges of frequencies displaced by substantially fixed amounts of frequency respectively from said given band of frequencies and said different bands of frequencies.

4. In a multi-band radio receiver circuit, a pair of inductances of different values, one of said inductances being variable, a plurality of capacitors, and switching means for selectively connecting a first of said capacitors in shunt with said one inductance or a second of said capacitors in shunt with said one inductance and said one inductance to an intermediate point on the other of said inductances to form a circuit tunable over a band of short wave lengths or a band of higher frequencies displaced from said band of frequencies of short wave length.

5. A tunable system for a multi-band receiver comprising a pair of circuits each comprising two inductances of different values, one of said inductances being variable, and a pair of capacitors, means in one of said circuits for selectively connecting one of said capacitors in shunt with said one inductance or the other of said capacitors in shunt with said pair of inductances in

series; and means in the other of said circuits for selectively connecting one of said capacitors in shunt with the variable inductance thereof or the variable inductance thereof to an intermediate point on the other of the inductances thereof and the other of the capacitors thereof in shunt with the other inductance thereof, said connecting means being arranged for simultaneous operation and said inductances and capacitors being of values to form circuits tunable respectively over a first band of short wave lengths or a second band of frequencies displaced upwardly in the frequency spectrum from said first band and ranges of frequencies displaced by substantially fixed amounts from said first or second bands.
